UNITED STATES PATENT OFFICE.

ABRAHAM POLLAK, OF FAR ROCKAWAY, NEW YORK.

DESIGN FOR A COMBINED VANITY COMPACT AND CIGARETTE LIGHTER.

Application filed February 29, 1928. Serial No. 25,618. Term of patent 7 years.

To all whom it may concern:

Be it known that I, ABRAHAM POLLAK, a citizen of the United States, residing at Far Rockaway, county of Queens, and State of New York, have invented a new, original, and ornamental Design for a Combined Vanity Compact and Cigarette Lighter, of which the following is a specification, reference being had to the accompanying drawing, forming part thereof.

Fig. 1 is an elevation of one side of a device embodying my invention;

Fig. 2 is a similar elevation of the opposite side thereof;

Fig. 3 is a top or plan view thereof.

I claim:

The ornamental design for a combined vanity compact and cigarette lighter, as shown.

ABRAHAM POLLAK.
